UNITED STATES PATENT OFFICE

FRED A. SCHMITZ, OF CANTON, OHIO, ASSIGNOR, BY MESNE ASSIGNMENTS, TO REPUBLIC STEEL CORPORATION, OF YOUNGSTOWN, OHIO, A CORPORATION OF NEW JERSEY

EDGE CONSTRUCTION FOR DESK TOPS AND THE LIKE

Application filed June 26, 1930. Serial No. 463,957.

This invention relates to a novel edge construction for desk and table tops and the like.

An object of the invention is to provide a table or desk top having a lightweight rigid edge construction, which is neat and attractive in appearance.

Another object of the invention is to provide an edge construction for desk and table tops consisting of a minimum number of inexpensively manufactured parts, which may be quickly and readily assembled without the aid of special tools or the use of screws, nuts, bolts or other fastening devices.

With the above and other objects in view, which will be more readily apparent as the nature of the invention is better understood, the same consists in the novel construction, combination and arrangement of parts hereinafter more fully described, illustrated and claimed.

A preferred and practical embodiment of the invention is shown in the accompanying drawing, wherein

Fig. 1 is a plan view of a desk top, showing the manner in which the binding strips are applied to the edges thereof;

Fig. 2 is a fragmentary cross-section through the edge of the desk top, taken on the line 2-2 of Fig. 1;

Fig. 3 is a perspective view of one of the spring clips used for retaining the binding strips in position, and

Fig. 4 is a plan view of one of the binding strips, prior to being applied to the edges of the desk top and bent into the desired shape.

Referring more particularly to the drawing wherein like reference characters designate like parts throughout the several figures, the desk top includes a metal top plate 1, to the upper surface of which is secured, as by cement, a linoleum cover 2, the edges of which are beveled as at 2a.

Secured as by spot welding to the lower surface of the top plate 1, near the edges thereof, are edge reinforcing members 3, each of which comprises an attaching flange 3a, a vertical web portion 3b, an inclined portion 3c, a depending apron 3d and an inwardly extending flange 3e.

The space between the top plate 1 and the vertical web portion 3b and inclined portion 3c of the edge reinforcing member 3 provides a pocket or recess A, into which resilient clips 4 extend. These clips are made of spring steel and are provided with tongues 4a which extend downwardly into suitable openings 3f in the reinforcing member 3, body portions 4b which rest on the inclined portion 3c of the reinforcing member, and terminal portions 4c of ogee curve formation as shown in Fig. 2. It will be understood that the spring clips 4 are properly positioned in the aforesaid manner before the edge reinforcing members 3 are welded to the top plate 1.

The ends of the edge reinforcing members 3 are mitred to permit them to be readily assembled to provide in effect a continuous rigid reinforcing frame, as shown in Fig. 1. In practice, the mitred joints are acetylene welded and ground to provide smooth finished corners.

Binding strips 5, preferably of brass or bronze, abut the edges of the top plate 1. Each of these binding strips is of angle cross-section, having a horizontal leg 5a and an inclined leg 5b. Portions of the horizontal legs 5a are cut away as at B to facilitate bending of the binding strips into the U-shaped form shown in Fig. 1. The inclined legs 5b of the binding strips conceal and protect the beveled edges 2a of the linoleum cover 2.

The binding strips 5 are applied to the edges of the desk top by forcing the horizontal legs 5a thereof into the pockets or recesses A, and in so doing, the terminal portions 4c of the spring clips 4 are forced downwardly, but owing to their inherent resiliency, spring back into the soft metal of the binding strips, as shown in Fig. 2, and securely hold the binding strips in contact with the edges of the top plate 1 and the linoleum cover 2. The ends of the binding strips may be bent into engagement with the edges of the desk top in the manner shown in Fig. 1.

In my copending application, Serial No. 451,268, filed May 10, 1930, which has resulted in Patent No. 1,885,554 of November 1, 1932, I have disclosed an edge construction similar to that shown and described in the present

- application, but utilizing prongs struck up from the metal of the edge reinforcing members to retain the binding strips in position. The separate spring clips used in the present construction are, however, much more resilient than the aforesaid prongs and are therefore more effective in preventing the binding strips from being pulled away from the edges of the desk top.
5. It is thus seen that a lightweight rigid edge construction is provided, which is neat and attractive in appearance, and which may be quickly and readily assembled without the aid of special tools or the use of screws, bolts, nuts, or other fastening devices.
- Without further description, it is thought that the features and advantages of the invention will be readily apparent to those skilled in the art, and it will of course be understood that changes in the form, proportion and minor details of construction may be resorted to without departing from the scope of the appended claims.
- I claim:
25. 1. In an edge construction for desk tops and the like, a top plate, a reinforcing member secured to the lower surface of said plate, a binding strip, and spring clips supported by said reinforcing member.
30. 2. In an edge construction for desk tops and the like, a top plate, a binding strip adjacent the edges of said top plate, a reinforcing member secured to the lower surface of said plate, and spring clips supported by said reinforcing member and having portions engaging said binding strip.
35. 3. In an edge construction for desk tops and the like, a top plate, a reinforcing member secured to the lower surface of said plate and having a portion thereof spaced from said top plate to provide a pocket or recess, a binding strip having a portion thereof disposed in said pocket or recess, and spring clips supported by said reinforcing member
40. 4. In an edge construction for desk tops and the like, a top plate, a reinforcing member secured to the lower surface of said plate and having a vertical web portion and an inclined portion spaced from said top plate; said top plate, vertical web portion and inclined portion defining a pocket or recess, a binding strip having a portion thereof disposed in said pocket or recess, and spring clips extending into said pocket or recess and in engagement with said binding strip to hold the latter securely in position.
45. 5. In an edge construction for desk tops and the like, a top plate, a reinforcing member secured to the lower surface of said plate and having a vertical web portion and an inclined portion defining a pocket or recess, a binding strip having a portion thereof disposed in said pocket or recess, and spring clips extending into said pocket or recess and in engagement with said binding strip to hold the latter securely in position.
50. 6. In an edge construction for desk tops and the like, a top plate, a reinforcing member secured to the lower surface of said plate and providing with said plate a pocket or recess adapted to receive a portion of a binding strip, and spring clips supported by said
- reinforcing member and having resilient portions adapted to engage the portion of the binding strip disposed in said pocket or recess.
6. In an edge construction for desk tops and the like, a top plate, a reinforcing member secured to the lower surface of said plate and providing with said plate a pocket or recess, a binding strip having a portion disposed in said pocket or recess, and spring clips supported by said reinforcing member and having resilient portions engaging said binding strip to hold the latter securely in position.
7. In an edge construction for desk tops and the like, a top plate, a reinforcing member secured to the lower surface of said plate and having a portion spaced from said top plate and providing with a horizontal portion of the top plate a pocket or recess adapted to receive a portion of a binding strip, and spring clips supported by said spaced portion of the reinforcing member having resilient portions adapted to engage the portion of the binding strip disposed in said pocket or recess.
8. In an edge construction for desk tops and the like, a top plate, a reinforcing member secured to the lower surface of said plate and having an inclined portion spaced from said top plate and providing with a horizontal portion of the top plate a pocket or recess adapted to receive a portion of a binding strip, and spring clips supported by the inclined portion of the reinforcing member having resilient portions adapted to engage the portion of the binding strip disposed in said pocket or recess.
9. In an edge construction for desk tops and the like, a top plate, a reinforcing member secured to the lower surface of said plate and having a portion spaced from said top plate and providing with a horizontal portion of the top plate a pocket or recess, a binding strip having a horizontal portion disposed in said pocket or recess, and spring clips supported by said spaced portion of the reinforcing member having resilient portions engaging said binding strip to hold the latter securely in position.
10. In an edge construction for desk tops and the like, a top plate, a reinforcing member secured to the lower surface of said plate and having an inclined portion spaced from said top plate and providing with a horizontal portion of the top plate a pocket or recess, a binding strip having a horizontal portion disposed in said pocket or recess, and spring clips supported by the inclined portion of the reinforcing member having resilient portions engaging said binding strip to hold the latter securely in position.
- In testimony whereof I affix my signature.
- FRED A. SCHMITZ.
